ARLINGTON MOORE, OF NEW YORK, N. Y., ASSIGNOR, BY MESNE ASSIGNMENTS, TO
MAXMOOR CORPORATION, OF NEW YORK, N. Y., A CORPORATION OF DELAWARE

CHARGE-SUPPLEMENTING APPARATUS FOR INTERNAL-COMBUSTION ENGINES

Application filed April 7, 1927. Serial No. 181,711.

My invention relates to a charge supplementing apparatus for internal combustion engines consuming volatile liquid fuel, such as so-called gasoline, for example.

5 The object of the invention is the provision of apparatus for supplementing the charge material supplied through the customary carburetor, by addition thereto of a mixture of air and exhaust gas of the engine, at temperatures and in quantities and proportions regulated and metered to obtain best results throughout the various ranges of engine operation.

10 The present application is an advance upon and development of my prior applications including, for example, application Serial No. 173,388, filed March 7, 1927, for charge supplementing apparatus for internal combustion engines, and comprises substantially a complete reorganization of the various elemental parts or functional subdivisions which cooperate to secure improved engine operation, especially in the respects referred to above, together with additional elemental parts now included for the first time.

15 The apparatus comprises means for taking a portion of the exhaust gas from the exhaust conduit, means for effecting heat exchange between exhaust gas and air so as to preheat the air constituting a part of the supplemental gases supplied during low power operation, metering mechanism operated adjunctively to throttling for controlling the make up and delivery of the supplemental gas additions, means for utilizing the kinetic energy of exhaust gas supplied for supplying cold air at and toward full power running of the engine, in some cases a radiation cooler for use at such times, means for delivering the supplemental gases into admixture with the fuel and air stream from the carburetor, and means for supplying at certain times fuel in addition to that supplied by the carburetor, the additional fuel being so supplied that its delivery is independent of high intake depression and air speed past a suction fuel jet. These various interdependent functional subdivisions will be de-

scribed in substantially the foregoing order. With the foregoing and related objects in view, my invention will be best understood from illustrative embodiments thereof, especially adapted for accessory equipment 55 of engines already in service, shown in the accompanying drawings, in which:

MEANS FOR TAKING EXHAUST GAS FROM THE EXHAUST CONDUIT

15 Where an impact or Pitot tube is inserted through the wall of an exhaust manifold to divert exhaust gas for use in charge supplementing, a certain amount of constriction of the exhaust manifold is unavoidable. According to the present embodiment of the invention, which is herein illustrated as more particularly suited for accessory apparatus for application to engines already in service, I interpose in the exhaust conduit, at the usual joint where the exhaust pipe is bolted on to the exhaust manifold, a chambered body of somewhat larger bore than the exhaust manifold, and make the connection for the impact or Pitot tube or the equivalent thereof within this chamber, which in place constitutes substantially a local enlargement of the exhaust conduit. In this way a portion of the exhaust gas can be taken from the exhaust manifold with the velocity and kinetic energy of the exhaust gas stream behind it, with little or no resulting constriction or backing up of the exhaust gas stream in the exhaust conduit.

40 Two forms of improved exhaust gas withdrawal means are illustrated, one in Fig. 1 and another in Figs. 3-6. In each case a hollow casting is bolted in between the exhaust manifold and the exhaust pipe. The chambered casting, being solidly fastened in this position with bolts, affords a firm and substantial support on the engine for my entire apparatus when supplied for accessory equipment therewith of old engines already in service. In the form shown in Fig. 1, the inserted casting is designated generally by the reference numeral 10; it has a chamber 12 therein of a diameter somewhat greater than the bore of the exhaust manifold 14, and comprises a Pitot tube portion 16 formed as an integral part of the casting, and having its mouth 18 directed against the flow of exhaust gas in the exhaust gas conduit 14. The passage 20 in such member 16 is of substantially funnel formation, being of greatest diameter at the mouth 18 and gradually tapering to a smaller section toward its opposite end, where it preferably terminates in an upwardly directed

horn 22, which is interiorly threaded at 24, and serves for receiving the threaded neck 26 of the stove 28 of the metering and heat exchange appliance, which is designated generally by the reference numeral 30. For purposes of identification, I preferably designate this substantially semi-circular impact tube of Fig. 1 with gradually decreasing taper or funnel formation as the "ram's horn" impact tube.

75 A second form of the exhaust gas withdrawal means is illustrated in Figs. 3, 5 and 6, which I prefer to designate as the "escorter" tube.

80 Same comprises a chambered casting 10' bolted in place as before, with a lateral horn or extension 22' interiorly threaded at 24' for attachment to stove 28. The inlet from casting 10' to horn 22' is divided into substantially upper and lower halves by the partial septum 32, providing a broad, gently curving inlet 34 directed against the flow of exhaust gas in the exhaust conduit 19', and a similarly curved return passage 36 directed with the flow of the exhaust gas stream in the exhaust conduit. Exhaust gas striking the concave upper surface 38 of septum 32 is forcibly driven out of horn 22' at 24' into the stove 28 when the passages therethrough are open, and a circulation of exhaust gas is secured through horn 22' and into and out of stove 28 and back into the exhaust conduit at 36 when the outlet passage through stove 28 is closed or nearly closed. Under such circumstances which exist at 90 and near closed positions of the throttle, as will be pointed out below, while only a small part of the exhaust gas passes through the stove to the engine intake, the heat of a much larger part of the exhaust gases is 95 utilized for preheating the air supplied to the intake. The provision of septum 32 and the opening 39 around the end thereof leading back to the intake conduit at 36 avoids putting substantial back pressure upon the 100 exhaust gases in the exhaust manifold.

MEANS FOR PREHEATING AIR BY EXHAUST GAS

105 The exhaust gas horn is surrounded by a jacketing member receiving warm air from around the exhaust conduit, and the passage from the jacketing member communicates with an exteriorly insulated air passage surrounding the stove 28, thus securing effective heating of air passing through these passages.

110 The elbow jacket 42 surrounding the ram's horn tube 22 of Fig. 1 communicates at 44 with the annular passage 46 surrounding stove 28 and leading to the preheated air metering port 48, and in this form two surrounding air chambers 50 and 52 serve for insulating and preventing undue heat loss. The same provision is made for heating air 115

in the form shown in Fig. 3, except that the jacketing tube 42' is substantially straight instead of elbow shaped. In Fig. 7 air passage 16^a surrounding stove 28 is in turn surrounded by the single air chamber 50^a for insulating purposes. The means for heat exchange are constructed and function by heat exchange through an intervening metallic wall in substantially the same way as in my prior application above referred to and do not require further detailed explanation.

METERING MECHANISM

The metering mechanism is improved in several ways, including use of cam means for operating the rotor, by metering the mixture of exhaust gas and preheated air as it leaves the rotor, as well as metering the respective gases as they enter the rotor, by forming the rotor with substantially straight-through passages for exhaust gas so as to avoid eddying currents and resulting retardation of the movement of exhaust gas through the rotor, particularly at and toward widest open positions of the exhaust gas ports of the rotor, and by passing the exhaust gas and the cold air freely through the rotor at and toward wide open throttle, at which times the metering of exhaust gas and cold air is substantially transferred to the induction apparatus making use of the kinetic energy of the exhaust gas to induce flow of cold air.

Cam control of metering mechanism

Operation of the metering mechanism by means of a simple crank interlinked with the throttle is somewhat lacking in flexibility of the control afforded of the supplemental gases, and I, therefore, preferably operate the metering rotor by means of a cam, and interlink the cam with the throttle. By making the cam readily removable so that it can quickly be replaced by another I obtain great flexibility of control and can, for example, cause the rotor to turn through angular distances which may be greater or less than the corresponding angular movements of the throttle, or produce a dwell of the rotor toward the latest or other turning movement of the throttle, etc. Thus I can inexpensively adapt my apparatus for use to best advantage with various carburetors and on various engines, and in any engine can vary the metering rotor movement obtained adjunctively to the turning of the engine throttle. In this way, by simply replacing one simple cheap cam with another, I can readily control the metering characteristics of the apparatus in practically any desired manner.

The preferred form of cam operating means for the metering rotor 60 is shown in Figs. 8 and 16, and comprises a lever

62 pivoted at 64 and having one leg 65 provided with a means such as an opening 66 for connection of a link 67 leading from the engine throttle crank 68. The other leg 70 of lever 62 contains a cam slot 72 for receiving the head 74 of crank 76 on rotor 60. When the lever 62 is turned, the rotor 60 turns, its movement depending on the form of cam slot 72. By removing pivot screw 64, the cam lever 62 can be immediately removed and replaced by another lever with a different form of cam slot. It will be evident that by shaping the cam slot 72 as desired, substantially any preferred movement can be imparted from the throttle to rotor 60.

The leg 70 of lever 62 may be made substantially rectangular as indicated at 70^a, Fig. 8, and when so formed the outlines of the piece need not be changed in blanking 85 out slots therein, there being sufficient material to take substantially any form of slot.

In Figs. 20 and 21 I have shown on an enlarged scale the lever 62 containing the cam slot 72 which in turning from the position of Fig. 21 to that of Fig. 20 first moves the rotor relatively quickly and then more slowly. Other forms of cam slots 72^b, 72^c and 72^d are shown in Figs. 18, 19 and 22 respectively, and each produces its own characteristic kind of rotation of rotor 60 corresponding to a radial turning of lever leg 65 upon actuation of the throttle.

This cam operating device for the metering rotor largely dispenses with need for 100 different models for different engines, and enables requirements to be met which would otherwise be very difficult to take care of.

Metering of mixture of hot exhaust gas and preheated air

Another feature of the present invention resides in the provision of improved metering means for the mixture of hot exhaust gas and preheated air, which constitutes the supplemental material for delivery into admixture with the fuel and air stream from the carburetor to the engine cylinders under conditions of light load or low part throttle opening. With the present invention the stationary portion of the metering mechanism 110 comprises as heretofore a set of four stationary ports, preferably formed in a sleeve 78 in which the rotor turns, there being an inlet port 48 therein for preheated air, and 120 an inlet port 82 for hot exhaust gas, and two outlet ports 84 and 86 therefrom, one thereof, 84, for delivery of a mixture of hot exhaust gas and preheated air direct to the conduit 87 leading to the engine intake, 125 and the other, 86, for controlling the passage of exhaust gas first into admixture with the cold air and then indirectly to the intake through conduit 87.

The metering rotor 60, however, instead 130

of having three ports as heretofore, has, according to the present invention, four ports, 80^a, 82^a, 84^a and 86^a, one of which ports contacts with each of the four stationary or sleeve ports, 48, 82, 84 and 86, and in particular I provide a distinct port 84^a in the metering rotor coacting with stationary port 84 for controlling the delivery of preheated air and exhaust gas direct to the delivery conduit 87 separately from the rotor port 86^a which controls the delivery of exhaust gas through stationary port 86 into admixture with cold air, and thence indirectly to the said delivery conduit.

The mixture of preheated air and hot exhaust gas formed in the rotor cavity 85 is metered by this additional port 84^a upon its delivery to the conduit 87 leading to the engine intake, and the leading edge 88 of this new port 84^a in the rotor is preferably an inclined or cleaver edge, so that registration and resulting opening of the passage through ports 84 and 84^a is gradual, beginning first at one end of port 84, and gradually enlarging as the port is further opened. By thus accurately metering the entire mixture of preheated air and exhaust gas passing at 84, 84^a from the rotor 60 to the delivery conduit 87, in addition to separately metering the preheated air as it is delivered to the cavity 85 within the rotor, at 80^a and the hot exhaust gas at the time of its delivery to the cavity within the rotor at 82^a, I am enabled with little or no additional expense to secure a much more accurate and certain control of the supplementer gases which are supplied to the engine intake at idling and under low load conditions, at which it is desirable to have the additional gases and especially the air component under as complete control as possible. The final heating of the preheated air component by direct admixture with the hot exhaust gas in the rotor cavity and consequent expansion of the air in such cavity prior to delivery through port 84^a enables a closer metering control to be had at port 84^a than at the air port 48, the air passing through port 48, though preheated, being denser than after being further heated by admixture with hot exhaust gas and delivery at 84^a.

This provision for metering the hot exhaust gas and preheated air can readily be traced across unrolled views Figs. 23-26, of the sleeve and rotor of the metering mechanism, the full line ports being the stationary or sleeve ports, the dotted line ports being the rotor ports, and the cross-hatched parts indicating the extent of opening or registration of these ports. Thus at idling (Fig. 23), only the preheated air opening 80^a registering with the advance slot portion 80^a of preheated air port 80^a and the narrowed advance portion of exhaust gas

port 82^a are open to admit preheated air and exhaust gas to the rotor, and the mixture thereof is metered to delivery pipe 87 by the advance or cleaver edge 88 of port 84^a coming into registration with port 82. Fig. 24 shows the further opening of these respective ports for a further partial throttle opening, whereas in Fig. 25, showing the situation for still further throttle opening, ports 84 and 84^a have passed one another and are closed and port 80 is nearly closed, and in Fig. 26, showing open throttle conditions, all three of these ports are closed off. By metering the preheated air and hot exhaust gas separately and admixing them in the rotor cavity 85 and then metering the mixture as it passes from the rotor to the delivery pipe, the supplemental gases made use of at idling and at low throttle openings are readily controlled as desired.

Straight-through passage in rotor for exhaust gas

While the rotor may be of tubular formation as heretofore, and is so shown in Figs. 1 and 7, I preferably avoid such tubular formation because of resulting production of eddy currents, and make the exhaust gas passage 90 (Fig. 3) through the rotor substantially direct thereacross, so that the exhaust gas can pass freely through the rotor with the full drive of the exhaust gas stream behind it, making its kinetic energy and velocity efficiently available for induction of cold air to be delivered as a part of the supplemental gases to the intake. Ports 80^a and 84^a need have no special provision for avoiding eddy currents, as they function only during relatively high intake depression and do not depend to any considerable extent on utilizing the drive of exhaust gas behind them.

Cold air passages in metering mechanism

The stationary ports 92 and 94 in the cold air end of rotor sleeve 78 and the coacting ports 92^a and 94^a in the rotor 60 are preferably formed at center distances of substantially 180° apart as shown in Fig. 11, so as to give a straight-through passage when open, and also to provide a double air seal at each side of the rotor 60 when closed, and thereby prevent the dense cold air leaking in and getting to delivery conduit 87 and the intake passage during idling, at which time the quantity of air that can be made use of is limited and it is essential that the air which is supplied shall be as hot as possible. For the same reason I preferably enclose the cold air end of the rotor 60 in a sealing cap or cover 96 (Fig. 9). With this arrangement I preferably arrange the return spring 98 for securing return of the rotor to closed position at the opposite end

of rotor 60 and behind the rotor crank 76, as shown in said Fig. 9.

INJECTION OF COLD AIR BY EXHAUST GAS

5 In my prior disclosures reliance has been placed on the rotary meter for metering control of the exhaust gas made use of to aspirate cold air therewith and also for metering the cold air. This same kind of control 10 is continued by the present invention from the first coming into operation of the means for admixing cold air with the exhaust gas and for a further degree of opening of the 15 metering rotor beyond such first admixture, the metering of the exhaust gas and air at and toward open throttle position being controlled entirely by the exhaust gas pressure and the 20 openings in the induction device for cold air and exhaust gas respectively. In this way 25 I am enabled to get substantially full velocity and kinetic energy of the exhaust gas and practically atmospheric pressure upon the air at the point of cold air induction, and dispense with the metering of these 30 gases by the rotor, except at first opening of the ports therefor, and for a further portion of opening of such ports, the ports, however, serving at and toward wide open 35 throttle substantially merely the functions of gates to let the exhaust gas and air pass freely therethrough. In this way the induction of the cold air by the exhaust gas at and toward open throttle can be much more effectively carried out, and flow of 40 larger quantities of cold air induced with smaller quantities of exhaust gas, which is desirable, particularly in a low-compression engine. Furthermore, the supply of supplemental gases is thus made responsive at 45 such times to the speed of the charge stream in the intake passage.

The size of the passage for exhaust gas and of the induction passage for cold air can be varied at will in a manner already disclosed by me, the apparatus being so constructed that the sleeves and nozzles controlling the size of these passages can be removed and replaced at will with others of any desired size or combination of sizes.

50 I have shown in Figs. 1 and 7 the aspirator arrangement as heretofore disclosed, including cold air nozzle 100, to which cold air admitted through the rotor ports 92, 94^a is supplied through the cold air passage 102, and exhaust gas venturi 104 of the customary Venturi form and such aspirators can be used, with the features of free passage of gases thereto, etc., above described and good results be obtained therewith. Preferably, however, the tubular member 106 for the exhaust gas passage around nozzle 100 is choked as shown at 108, Fig. 3, beyond the point of cold air outlet at the end of nozzle 100, and with such choke bore as indicated at 108 and with expansion to

a large volume therefrom at 110 I have been able to inject air to the extent of three or four times by weight the quantity of exhaust gas. A funnel such as 112, Fig. 7, can be used to collect the cold air supply by exposure to a blast from any source, as of wind velocity due to vehicular motion, etc.

The described metering effects obtained first by the exhaust gas and cold air metering by the rotor followed by metering at the injector with the rotor openings serving substantially merely as gateways will be plain from the showing of Figs. 25, 26, 27 and 28. As the rotor is turned so that the preheated air port 80 and delivery port 84 direct to the conduit 87 are commencing to close, the cold air ports 92 and 94 begin to open simultaneously and are shown partly open in Fig. 25, being closed in Figs. 23 and 24. The port 86 for exhaust gas to the injector also opens along with the cold air ports 92 and 94. So long as these openings are not substantially in excess of the exhaust gas and cold air passages 114 and 116 of the injector 118, the metering for the exhaust gas and cold air which come together at the injector 118 is done by the rotor, being controlled by extent of opening of rotor ports. The light arrows 120 in Fig. 27 indicate that at the rotor position of Fig. 25 immediately over Fig. 27 there is less than full driving power on the exhaust gas. When, however, as shown for full throttle position in Fig. 26, the exhaust gas and cold air openings in the rotor are open to an extent substantially greater than the injector passages 114 and 116, these ports become gates only, the full effective driving action is imparted to the exhaust gas, as indicated by the heavy arrows 122 on Fig. 28 immediately over Fig. 26, and is effectively used for injecting cold air. During such period the quantities of exhaust gas passed and cold air induced, while passing through fixed openings 114 and 116 will increase with increase of velocity and pressure of the exhaust gas stream, and with increase of stream velocity toward the engine cylinders in the intake passages, the supplemental gases being delivered to the intake in the direction of flow therein.

COOLER

Inasmuch as maximum cold air supply depends upon efficient injection, and this in turn depends on maximum volume shrinkage of exhaust gas at the injector, which calls for delivering the exhaust gas to the injector at as high a temperature as possible, I prefer, particularly with low-compression engines to dispense with radiation coolers for the exhaust gas and to rely upon supplying sufficient cold air with the exhaust gas to reduce its temperature sufficiently to ensure getting full volumetric effi-

ciency under relatively heavy load conditions.

In Fig. 3 I have shown a jacket 124 enclosing an insulating air space 126 surrounding the exhaust gas passage 128 to the injector to ensure delivery of the exhaust gas to the injector at the maximum temperature available. With such arrangement, by delivering the exhaust gas at maximum temperature to the air injector nozzle, maximum shrinkage and air injection are obtained.

With high-compression engines, however, the proportion of exhaust gas to cold air which can be supplied at heavy engine loads without detonation is relatively higher. In such cases and when the resulting temperature after passing through the injector nozzle cannot be readily kept below the condensation temperature of steam at the pressures encountered, I preferably make use of a cooler, comprising heat radiating fins 130, as shown in Figs. 7, 8 and 9, for cooling the exhaust gas and/or the mixture of cold air and exhaust gas. For intermediate conditions of compression ratios I may dispense with both cooling fins and insulating jacket, and make use of a plain casting as indicated at 132, Fig. 1. It will be understood, however, that in each case the supplementary gases supplied when the compression pressures are high enough to normally be accompanied by detonation, are cooled sufficiently by admixture of cold air with the exhaust gas and by any needed amount of cooling through heat radiating surfaces to prevent substantial loss of volumetric efficiency, while at the same time providing heat sufficient for gasifying the fuel.

40 DELIVERY OF THE SUPPLEMENTAL GASEOUS MIXTURES TO ENGINE INTAKE

The mixtures of gases provided by the metering mechanism including the injector are delivered through the delivery pipe 87 to the engine intake. Pipe 87 may be attached to the appliance 30 either at the front or side, as desired, the front opening 134 being plugged when pipe 87 is connected at the side opening 136 and vice versa. This facilitates the attachment of the apparatus as an accessory to various makes of engines, etc.

The supplementer gases are preferably delivered to the intake conduit above the throttle. In effecting their delivery it is desirable that no substantial constrictions be imposed in the intake conduit passage for the fuel and air stream coming from the carburetor, also that the supplementer gases be discharged in the direction of stream flow in the intake conduit, and that in their discharge the maximum agitation and gas admixture be attained. I may effect these results to a sufficient extent by

enlarging the intake conduit from dotted line to full line dimensions, as diagrammatically indicated at 138, Fig. 1, and discharging upwardly through nozzle 140 formed in a cross member 142 and providing inclined or rifled vanes 144 to produce agitation and admixture of charge components.

The preferable arrangement, however, is shown in Figs. 3 and 4, in which the supplementer gases are delivered from pipe 87, through an annular passage 146 formed between the thin tube 148 for conducting the fuel and air stream from the carburetor, and the cylindrical walls of a casting 150 to which the supplemental gases are delivered substantially tangentially through the elbow 158 to which pipe 87 is connected.

The supplemental gases set into cyclonic agitation by tangential delivery to annular passage 146, issue from the annular passage 146 around the mouth of the thin tube 148 and become thoroughly admixed with the fuel and air stream.

I preferably form the intake conduit in this neighborhood with a first gradually enlarging part 154 followed by a gradually narrowing portion 156. The expansion and contraction produced in this neighborhood, together with the cyclonic agitation produced at the issuance of the supplementer gases from the annular nozzle 146 all serve to produce a highly effective admixture of the supplemental gases with the fuel and air stream from the carburetor.

It will be observed that the thin tube 148 through which the fuel and air stream from the carburetor passes is surrounded at partial throttle openings with a hot mixture of hot exhaust gas and preheated air, which changes as the throttle is further opened to a cool mixture of exhaust gas and cold air. The tube 148 being thin responds readily to its jacketing temperature and imparts heating to the fuel and air stream for low partial throttle openings and correspondingly low initial cylinder pressures, whereas when the throttle is opened wider and the charge is desirably more dense to get higher initial pressures and substantially maximum volumetric efficiency, the fuel and air stream from the carburetor is automatically cooled by its jacketing gases, or at least is not materially heated. This automatically takes care of requirements for imparting heat to the fuel and air stream, making an efficient hot spot arrangement during low load operation and a cold spot for higher load operation automatically adapted to the heat needs of the charge mixture.

AUXILIARY FUEL SUPPLY

With the supplementing charge gases supplied above the throttle, it is of course

characteristic of my charge supplementing apparatus that the intake depression is much less, or in other words, that the intake pressures are much nearer to atmospheric pressure, than in the case of the ordinary engine, in which the entire charge material is delivered from below the throttle and passes by the throttle on the way to the engine cylinder. This is advantageous from many standpoints, particularly in the resulting decrease of tendency to oil pumping, in the fact that power which would otherwise be expended in pumping losses is saved, and because of improvement in engine operation due to increased initial cylinder pressure.

I preferably go further than this and purposely make use of intake manifolds and carburetors of greater bore diameter than 20 customarily used, in order to obtain a substantially complete cylinder filling and as low intake depression as is practicable. In Fig. 1 I have indicated in full lines and in dotted lines respectively relative carburetor 25 venturi passage openings for use with my system as compared with the size ordinarily used.

I have found that the advantageous features resulting from lowered intake depression 30 can be secured to their optimum extent only with the sacrifice of ability to raise fuel by suction on a fuel jet located in the customary position below the throttle, at times when the intake depression is already 35 especially low, particularly at starting, and upon opening the throttle from a constant running setting to a wider opening for purposes of obtaining acceleration. This is particularly true if, as is desirable, the carburetor fuel jet is adjusted "lean" to provide 40 a desirably economical mixture, and it can happen at times that engines equipped with my supplementer apparatus cannot be started, at least not without a great deal of 45 difficulty, and instead of accelerating when the throttle is opened for that purpose, the air will come through alone or largely alone, the heavier fuel lagging behind temporarily due to its greater inertia, and the engine 50 will initially choke and spit and may even stop, instead of accelerating as desired.

In order to dispose of difficulties of this sort, I have devised means for auxiliary fuel supply which are automatically operated adjunctively to throttling, and which can be used to supply auxiliary fuel in limited quantities into suspension in the stream within the intake conduit, when the throttle is opened either for starting or for 55 accelerating.

Upon decelerating or return movement of the throttle, a reverse situation is encountered: the fuel, by reason of its greater inertia, tends to continue to come through 60 even after the air is partially shut off, so

that if auxiliary fuel were supplied upon such throttle movements, it would richen the mixture unduly. I therefore make provision for securing the return of the throttle and of the supplementer rotor without such return movement being productive of the feeding of auxiliary fuel. I also make provision for renewing the supply of auxiliary fuel, which is fed into the engine intake under a pressure or gravity head, so that this supply is immediately renewed upon any return movement of the throttle, however small, thus making it possible to accelerate repeatedly without intermediate closing or substantial closing of the throttle. 70 75 80

The auxiliary fuel is supplied without reliance upon intake depression and air velocity on a fuel jet and is desirably positively delivered to the intake conduit, as for example by maintaining the auxiliary fuel supply above its point of delivery to the intake conduit and merely releasing it, or in other words, opening up the fuel passage when the auxiliary fuel is required, whereupon it is positively fed under a gravity 90 head and without any delay such as would be incident to picking up or lifting fuel by suction on a jet.

I have illustrated a preferable form of auxiliary fuel feeding apparatus in Figs. 1 95 and 2. Such apparatus as shown comprises a fuel well 158 having its outlet to the intake conduit 160 through a pipe 162 controlled by a needle valve 164, and the supply of fuel to the well from a constant level 100 source, such as a vacuum tank, adapted to normally maintain a level in the well as indicated in dotted lines at 166 in Fig. 1, controlled by a second needle valve 168, which two valves may be conveniently designated 105 as the delivery and the supply valves respectively.

Valve 164 is pressed downwardly by a spring 170 and valve 168 is pressed upwardly by a lighter spring 172, and the lever 174, 110 pivotally connected to both valves, is operated by a plunger 176, also pivoted to said lever 174. Plunger 176 is pivotally connected to a second lever 178, which has a roller 180 running in inclined slots 182 in 115 said lever 178, and said roller is engaged by projections 184 and 186 of a cam 188, which is operated from the engine throttle as by a crank 190 and a link 192.

Turning movement of the cam 188 in a 120 direction to force roller 180 toward the lower end of the slot ways 182 results in actuation of plunger 176 and valves 164 and 168 to close the supply valve 168 and open delivery valve 164, whereas upon reverse or decelerating movement of the throttle and corresponding movement of cam 188 the roller 180 moves toward the higher end of the slots 182 and merely rides up on the cam 130

projections 184 and 186, without actuating the fuel valves.

The cam projection 184 is relatively sharp and encounters roller 180 and works the valves to release fuel and shut off the supply to the well upon a relatively small throttle opening, whereas projection 186 is wider and does not come into action unless the throttle is opened fairly wide.

10. An important characteristic of this auxiliary fuel feeding apparatus is that it is not necessary to close the throttle between successive periods of accelerating throttle movement in order to secure delivery of fuel for purposes of acceleration, but one may accelerate and supply additional fuel therefor repeatedly without intermediate closing or substantial closing of the throttle.

15. The subdivision of the auxiliary fuel at delivery to the stream flow in the intake conduit can be accomplished in various ways. In Fig. 1 the pipe 162 for supplying the auxiliary fuel leads to and delivers from a plurality of fine drilled holes 194 in the cross member 142 and the auxiliary fuel supply may also be delivered from a jet 196 arranged centrally of the nozzle 140 provided for supply of supplemental gases to the intake conduit.

20. In the form of Fig. 3 the auxiliary fuel pipe 162 has a minute air vent 198 through the jet adjusting needle 200 and delivers the fuel, broken up with air bled through opening 198, through a series of openings 202 provided in the sleeve 204 surrounding the annular nozzle 156 provided for discharge of supplementing gases to the engine intake. These modes of delivery are by way of example only, and various nozzles and arrangements for auxiliary fuel delivery may be resorted to, as for example I may make use of a simple tubular nozzle 206 with the end plugged and having minute laterally directed fuel openings 208 as shown in Fig. 25. 30, and the fuel may be delivered in various other ways.

The auxiliary fuel feeding means is not claimed herein, having been described and claimed in my applications Serial No. 164, 50 349, filed January 28, 1927, and Serial No. 176,410, filed March 18, 1927, and Serial No. 188,326, filed May 2d, 1927.

It will be seen that all the functional subdivisions hereinabove coact to secure the 55 beneficial results which have been set forth, but it will at the same time be understood that changes and modifications can be resorted to within the scope of my claims.

I claim:

60. 1. In a charge supplementer for internal combustion engines, valve means for controlling passage of air and exhaust gas into the stream to the engine cylinders, exteriorly exposed replaceable cam means adapted to be moved for operating said valve means, and

means for operating said cam means adjunctively to engine throttling, whereby substantially any desired interrelation between the throttle and valve means may be readily obtained.

2. In a charge supplementer apparatus for internal combustion engines, an intake conduit, means for supplying a fuel and air stream therethrough, an annular nozzle for a mixture of exhaust gas and air leading into the intake conduit about the walls thereof, said conduit having a first enlarging and then a contracting section beyond the nozzle outlet whereby the streams are churned together and thereby admixed.

3. In a charge supplementer for internal combustion engines, means for supplying exhaust gas into the stream to the engine cylinders, valvular means for controlling the passage of exhaust gas therethrough, replaceable cam means for operating said valve means, and means for operating said cam means adjunctively to engine throttling, whereby substantially any desired interrelation between the throttle and valve means may be readily obtained.

4. The combination with the intake conduit, throttle and fuel delivering means of an internal combustion engine, of a venturi member in said intake conduit beyond the 95 throttle, a tubular portion disposed within said intake conduit beyond the throttle and extending into said venturi, said intake conduit and said tubular portion forming a passage having a relatively constricted discharge orifice substantially at the constriction of said venturi, and means for supplying supplementary gases through said passage.

5. In a charge supplementer for internal 105 combustion engines, a tubular member through which the fuel and air stream from the carburetor is passed on the way to the engine cylinders, means for delivering a substantially annular stream of exhaust gas 110 and air about said tubular member and into admixture with the fuel and air stream beyond the end of the tubular member, and means for controlling the temperature of said mixture of exhaust gas and air to supply the same substantially hot for low engine loads and substantially cool for high engine loads.

6. In a charge supplementer for internal 120 combustion engines, an intake, a venturi therein, an elongated tubular member in said intake through which the fuel and air stream from the carburetor is passed, the upper end of said tubular member extending into said venturi in spaced relation 125 thereto to form an annular discharge orifice, means for delivering a substantially annular stream of exhaust gas and air to the engine intake around said tubular member and into admixture with the fuel and air stream 130.

beyond the end of said tubular member, whereby heat interchange is effected between the stream of exhaust gas and air and the stream of fuel and air prior to the admixture of said streams, and means for controlling the temperature of said mixture of exhaust gas and air to supply the same hot for low engine loads and cool for high engine loads.

10 In testimony whereof, I have signed my name hereto.

ARLINGTON MOORE.
